STEAM BOILER

Constantine Alexandrou, Brooklyn, N. Y.

Application October 6, 1942, Serial No. 460,989

4 Claims. (Cl. 122—333)

This invention relates to steam boilers.

An object of my invention is to provide a steam boiler embodying a novel water circulating structure operating to render the boiler highly efficient, economical in the matter of fuel consumption and maintenance cost.

In the accompanying drawings:

Figure 1 is a vertical longitudinal section through a steam boiler constructed in accordance with my invention;

Figure 2 is a vertical transverse sectional view through the same, and

Figure 3 is a fragmentary horizontal section through the same.

In the embodiment selected for illustration I employ a bottom horizontal header 128 having communication with an upper header 130 through the medium of a plurality of, in the present example four, tubes 132. The headers are of cylindrical closed end type with the upper disposed vertically above and parallel with the lower horizontal header and the tubes 132 extending vertically therebetween and having communicative connection therewith. A multiplicity of pipes 134 of substantially reduced diameter, with reference to the tubes 132, also connect with the top and bottom headers, these pipes being of angular approximately U-shaped formation and having their upper and lower ends in communication with the respective header chambers. The pipes 134 are arranged in banks lying in planes at right angles to the axes of the two headers. Thus water is caused to descend in the tubes 132 and flow upwardly in the tubes 134 from the header 128 and discharge into the header 130.

The boiler structure is enclosed in a brick shell 136, the bottom portion of which constitutes a firebox. The lower header 128 is, as shown in Figure 1, supported by steel beams 137 which are carried by brick walls 138, such walls extending transversely of the header. This header is also supported by brick walls 138a which extend longitudinally of the header, as shown in Figure 2. A semicircular body of insulation 140 covers the header 128 throughout its length and slightly less than one hundred and eighty degrees of its circumference as a protection against excessive heating at the lowest point of the boiler. A similar body of insulation 142 covers the upper half of the header 130.

A plurality of steam pipes 144 communicate with the upper part of the header 130 and are bent downwardly and coiled at 146 and then extended upwardly through the top structure 148 of the shell 136 for communication with a steam

chamber 150 enclosed in an insulative chamber 152 mounted on the top structure 148. An outlet 154 for superheated steam has communication with the chamber 150. This chamber is also provided with a connection 156 for a safety valve. Communicating with the header 130 is a boiler steam connection 158, which header is also provided with a connection 160 for a safety valve.

Arranged vertically at one end of the boiler structure comprising the headers 128 and 130 and the tubes 132, together with the water circulating tubes 134, is a water preheating drum 162 having a pipe 164 communicating with its upper end and extending inside the header 130 and shaped with a horizontal portion 166 provided with nozzles 168 extending short distances inside the upper ends of the tubes 132.

A feed water pipe 170 has communication with the drum 162 and may be connected with a suitable pump (not shown) for forcing water into the boiler structure. This drum is provided with a connection 172 for a safety valve and is provided with a manhole structure 174 in its upper end, together with a drain pipe 176 at its lower end.

To preheat water in the drum 162 for delivery to the boiler structure, two tube banks 178, each comprising a plurality of U-shaped and horizontal tubes 180, are arranged on opposite sides of the tubes 132. All the tubes have communication with the drum 162, and each tube is arranged so that one leg thereof is positioned vertically above the second leg thereof to facilitate circulation of the water.

In Figure 2, the two banks 178 are housed in vertical walls 182 extending back to the wall 184 of the shell 136 on both sides of the drum 162. However, the opposite ends of the walls terminate some distance short of the reverse bends of the tubes 180. Angular walls 186 extend from the lower edges of the vertical walls 182 down to the header 128 adjacent the tubes 132.

Between the upper and lower legs of the tubes 180 in the two banks 178 are arranged dividing walls 188 declining slightly from the tubes 132 to positions closely adjacent the vertical walls 182. The walls 188 are relatively short and are located intermediate the ends of the tubes 180. Hot gases flow upwardly about the tubes 134 and reversely of the tubes 188 and pass through an outlet opening 190 controlled by a damper 192. The hot gases circulating upwardly about the tubes 134 are largely isolated from the tubes 180 by reason of the walls 182 and 186. Thus the greater portion of the hot gases is first brought into heating

relationship with the tubes 134, as well as with the superheater steam tubes 144 before passing about the tubes 180.

The drum 128 is provided with a manhole structure 194, and a similar manhole structure 196 is provided for the drum 130. The latter drum is provided with a U pipe 197 having a gage glass 198. A pipe 200 extends inside the drum 130 to skim the surface of the water.

The boiler which is preferably heated by oil, has the front brick wall 201 thereof provided with openings 202 for the reception of oil burners of any well known or appropriate construction.

Without further elaboration, the foregoing will so fully illustrate my invention, that others may, by applying current knowledge, readily adapt the same for use under various conditions of service.

I claim:

1. In a boiler, a housing, a pair of elongated headers mounted horizontally in the upper and lower parts of the housing, a plurality of vertical tubes of relatively large interior diameter connected to the headers at longitudinally spaced intervals and providing communication therebetween, a multiplicity of tubes of relatively small interior diameter connected to and providing communication between said headers, said smaller diameter tubes having their intermediate portions offset laterally to provide spaces between the same and the vertical tubes, a feed water pre-heating container mounted adjacent one end of the headers, and a plurality of conduits having their ends connected with upper and lower portions of said feed water container and extending through the spaces between the vertical tubes and the offset portions of the smaller diameter tubes.

2. In a steam boiler, the combination of a furnace shell, a bottom header, a top header spaced vertically above the bottom header, each of said headers comprising a horizontally positioned drum, a plurality of vertical tubes connected with and providing communication between said top and bottom headers, said tubes, being spaced longitudinally of the headers, a plurality of vertically disposed water circulating pipes communicating at their lower ends with said bottom header and at their upper ends with said top header, a superheated steam chamber above the top header, and superheated steam pipes communicating at one end with said top header and at their other end with said superheated steam chamber, said headers, the vertical water circulating pipes and said superheated steam pipes being located inside said furnace shell to be heated by the hot gases of combustion therein, said superheated steam pipes extending downwardly from the top header about said water circulating tubes and upwardly to the superheated steam chamber.

3. In a steam boiler, the combination of a fur-

nace shell, a bottom header, a top header spaced vertically above the bottom header, each of said headers comprising a horizontally positioned drum, a plurality of vertical tubes connected with and providing communication between said top and bottom headers, said tubes being spaced longitudinally of the headers, a plurality of vertically disposed water circulating pipes communicating at their lower ends with said bottom header and at their upper ends with said top header, a superheated steam chamber above the top header, superheated steam pipes communicating at one end with said top header and at their other end with said superheated steam chamber, said headers, the vertical water circulating pipes and said superheated steam pipes being located inside said furnace shell to be heated by the hot gases of combustion therein, said superheated steam pipes extending downwardly from the top header about said water circulating tubes and upwardly to the superheated steam chamber, a water pre-heating drum, a plurality of U-shaped pipes communicating at their ends with said water pre-heating drum with one horizontal leg of each height positioned vertically above its other leg, said U-shaped pipes being grouped between the vertical tubes and the water circulating pipes, walls extending upwardly from the bottom drum and between said U-shaped pipes and said water circulating pipes, and substantially horizontal walls dividing portions of all the upper legs of the U-shaped pipes from the lower legs thereof.

4. In a steam boiler, the combination of a furnace shell, a bottom header, a top header spaced vertically above the bottom header, each of said headers comprising a horizontally positioned drum, a plurality of vertical tubes connected with and providing communication between said top and bottom headers, said tubes being spaced longitudinally of the headers, a plurality of vertically disposed water circulating pipes communicating at their lower ends with said bottom header and at their upper ends with said top header, a superheated steam chamber above the top header, superheated steam pipes communicating at one end with said top header and at their other end with said superheated steam chamber, said headers, the vertical water circulating pipes and said superheated steam pipes being located inside said furnace shell to be heated by the hot gases of combustion therein, said superheated steam pipes extending downwardly from the top header about said water circulating tubes and upwardly to the superheated steam chamber, and insulation about the upper substantially half portion of the top drum and about the bottom substantially half portion of the bottom drum.

CONSTANTINE ALEXANDROU.
